DEAERATING AND DISPENSING SLURRY

Thomas F. Mooney, New Lexington, Ohio, and David H. Innes, Matawan, N. J., assignors to Owens-Illinois Glass Company, a corporation of Ohio

Application April 28, 1949, Serial No. 90,128

4 Claims. (Cl. 222—389)

1

Our invention relates to a method and apparatus for deaerating or removing excess air or gases from slurry or liquified mixtures of structural materials. The invention is particularly adapted for use in treating structural materials which are to be molded for use as insulating slabs, building blocks, and the like. The slurry which is to be treated is made by mixing the ingredients with water to a desired consistency adapting it to be run into molds in which the material sets or hardens under suitable treatment. In the process of making the slurry, an undesirable amount of air is introduced which results in surface bubbles or blisters, and lack of homogeneity and other objectionable features in the final product. The present invention provides an apparatus and method for deaerating the slurry to a desired degree.

A preferred form of construction for use in deaerating slurry in accordance with our invention, comprises a vacuum chamber in the form of a horizontally disposed cylinder, means for exhausting the air therefrom to a desired degree, means for running the slurry from a supply tank into the vacuumized cylinder while the desired degree of vacuum is maintained and thereby extracting from the slurry the excess air or gases that have been entrained or mixed with the slurry. When a desired amount of slurry has been introduced, the supply is cut off, the vacuum line closed, and the slurry run through a valve controlled discharge pipe into molds, under an increased air pressure applied within the cylinder. The pressure is applied by a plunger piston working in the cylinder and actuated by a piston motor comprising a cylinder and piston, the latter connected to or formed integral with the first mentioned piston. Suitable means are provided for locking the pistons against movement during the deaerating operations.

The precise nature of the invention and various features of novelty embodied therein will be more fully understood from the following detailed description.

Referring to the accompanying drawings:

Fig. 1 is a part sectional elevation of a preferred form of apparatus for practicing our invention, parts of the apparatus being broken away.

Fig. 2 is a section at the line 2—2 on Fig. 1. The apparatus in its preferred form comprises a horizontal cylinder 10, herein termed a vacuum cylinder, bolted to standards 11 mounted on base 12. A piston 13 which is in the form of a hollow cylindrical plunger is closed at its inner end and

10 is mounted to reciprocate within the cylinder 10. A packing gland 14 provides an airtight seal between the piston and cylinder. The piston 13 is driven by a piston motor comprising a cylinder 15 and a plunger piston 16 connected in tandem with the plunger 13. The cylinder 15 is mounted in horizontal alignment with the cylinder 10, being bolted to standards 17 on the machine base 12. The piston 16 as shown, is a hollow cylindrical plunger, closed at its inner end, its opposite end being rigidly attached to or formed integral with the piston 13. A packing gland 18 provides an airtight seal between the motor cylinder and piston.

15 A lock ring 21 is provided to grip the piston 16 and prevent movement of the pistons during the deaerating of the slurry as hereinafter described.

The lock ring is mounted on a standard 22 and as shown in Fig. 2, comprises a lower section 23 bolted to the standard and an upper section 24 adapted to be drawn down into clamping engagement with the piston 16 by bolts 25 threaded into the section 23. By loosening the bolts 25 the lock ring is released to permit free lengthwise movement of the piston 16 therethrough.

20 Air under pressure for driving the pistons and for supplying pressure within cylinder 10 for other purposes presently to be described, is supplied through an air pressure supply pipe 26 leading from a source of air pressure (not shown) to a three-way control valve 27. An air pressure pipe line 28 extends from the valve 27 to the head 29 of the cylinder 10 through which it opens into the vacuum chamber. A hand valve 30 is provided in the line 28. A second pressure pipe line 32, which may be opened and closed by a hand valve 33, extends from the valve 27 to the outer end of the cylinder 15 and supplies air 25 under pressure for driving the pistons to the right. A hand lever 34 connected to the valve piston 35 is operable to connect the pressure line 26 with either of the cylinders 10 and 15. With the valve in the position shown, the pressure is supplied to the cylinder 15. When the lever 34 is moved to the right, the air pressure is cut off from the line 32, the latter is opened to an exhaust port 36, and the pressure line 28 is opened to the cylinder 10.

25 The cylinder 10 may be vacuumized to any desired degree by exhausting the air therefrom through a vacuum pipe line 37 connected to a vacuum pump (not shown). A hand valve 38 is provided to close the vacuum line.

30 Slurry is fed to the vacuum cylinder 10 from

a supply tank 40 through an inlet pipe 41 leading from the tank to the cylinder and provided with a shut-off valve 42. A stirring device 39 within the tank 40, keeps the contents mixed, preventing separation of the fluid and solids, or settling out of heavier constituents of the mixture. An air pipe 43 is connected at one end to the pipe 41 and is open at its opposite end but may be closed by a valve 44. The slurry is run from the tank 10 through a discharge pipe 45, opened and closed by a hand valve 46, into molds 47 or other containers. The plunger 13 is at this time in its retracted position, leaving the inlet opening at the lower end of the pipe 41 uncovered. An endless belt conveyor 48 serves to carry the molds to and from a charging position beneath the pipe 45.

The operation is as follows:

Assuming that the tank 10 is empty, and that the valves 42, 44, 38 and 46 are all closed, the operator moves the operating lever 34 of the three-way valve to the right, thereby opening pressure supply pipe 26 to the air pressure line 28 so that air pressure is admitted to the cylinder 19. The pistons 13, 16 are thereby moved to the left while the air from the cylinder 15 is discharged through the line 32 and exhaust port 36. The lock ring 21 is then clamped to the piston 16 and the air pressure line 28 is closed by the valve 39 or the three-way valve. The vacuum valve 38 is next opened to exhaust air from the tank 10 and produce the desired degree of vacuum. As the piston 13 has been moved to the left, as indicated in broken lines it clears the inlet pipe 41. The hand valve 42 is next opened sufficiently to permit the slurry to flow into the vacuumized tank, preferably in a rather thin stream so that the slurry as it enters the tank and passes through the rarefied air therein, is deaerated.

When the tank has been filled to a desired level the valve 42 and vacuum valve 38 are closed. The lock ring is then released from the piston, allowing a slight movement of the latter under the influence of the partial vacuum within the tank until equilibrium is established in the two tanks. If preferred, the valve 44 may be opened momentarily to balance the pressure in the tanks, before the lock ring is released. After the lock ring is released, the three-way valve is shifted to the left, namely, to the position shown in Fig. 1, so that air pressure is supplied through the line 32 and applied to the piston 16, thereby moving the pistons and building up air pressure within the cylinder 10.

The slurry can now be dispensed from the cylinder 10 in regulated amounts by intermittently opening and closing the hand valve 46, while constant superatmospheric pressure is maintained within the tank. The material as it is discharged may be received into the molds 47 brought in succession beneath the discharge pipe.

A further mode of operation consists in introducing into the tank 10 a sufficient amount of slurry to form a single mold charge. In this instance a comparatively large mold may be used commensurate with the size of the tank 10. If desired the slurry may be withdrawn from the tank under atmospheric pressure obtained by opening the valve 44 after the valve 42 and the vacuum valve 38 are closed. Releasing of the lock ring 21 is then unnecessary.

Modifications may be resorted to within the spirit and scope of our invention.

We claim:

1. Apparatus for dispensing slurry comprising

a cylinder, a plunger mounted to reciprocate into and out of said cylinder, means for locking said plunger in a retracted position, an inlet pipe opening into said cylinder, means for flowing slurry through said pipe into the cylinder, a discharge pipe through which the slurry is discharged under pressure, a piston motor for applying pressure to the plunger and thereby discharging the slurry, said piston motor including a cylinder and a piston connected in tandem with said plunger, a control valve, an air pressure supply pipe connected to said valve, pressure pipe lines extending from said valve to the outer ends of the cylinders respectively, said valve including a valve piston movable into positions to connect said pressure pipe lines alternatively to said pressure supply pipe and thereby alternatively apply air under pressure to the piston motor for discharging the slurry and to the plunger for returning said plunger to its retracted position.

2. Apparatus for dispensing a liquefied material or mixture, said apparatus comprising a horizontally disposed cylinder having a stationary mounting, a plunger mounted for horizontal reciprocation into and out of the cylinder, a piston motor for driving said plunger, said motor comprising a motor cylinder in alignment with said first-mentioned cylinder and a piston connected in tandem with said plunger, a locking device for locking the plunger in a retracted position, a supply tank, an inlet pipe extending from the first-mentioned cylinder to the supply tank and through which slurry is admitted to the cylinder, a discharge pipe extending from the cylinder, means for supplying pneumatic pressure to the motor cylinder and piston for moving the plunger inwardly and thereby applying pressure to the slurry and discharging it under said pressure through said discharge pipe, and means for supplying pneumatic pressure to the first-mentioned cylinder and the plunger to return the plunger to its retracted position after the discharge of the slurry.

3. The combination of a cylinder, means for mounting the cylinder in a fixed horizontal position, a plunger mounted to reciprocate within said cylinder, a plunger motor for driving said plunger, said motor including a horizontal cylinder mounted in fixed position in alignment with said first-mentioned cylinder and a driving plunger connected to said first-mentioned plunger, a locking ring encircling one of said plungers, a standard on which the locking ring is mounted, means for clamping the ring to the plunger and thereby locking the latter against lengthwise movement, means for flowing a liquid into the first-mentioned cylinder, means for actuating the said motor and thereby causing said first-mentioned plunger to apply pressure within the cylinder, means for withdrawing the liquid under said pressure from the cylinder, and means for applying pneumatic pressure to said first-mentioned plunger and returning it to its retracted position.

4. The combination of a cylinder, means for mounting the cylinder in a fixed horizontal position, a plunger mounted to reciprocate within said cylinder, a plunger motor for driving said plunger, said motor including a horizontal cylinder mounted in fixed position in alignment with said first-mentioned cylinder and a driving plunger connected to said first-mentioned plunger, a locking ring encircling one of said plungers, a standard on which the locking ring is mounted,

means for clamping the ring to the plunger and thereby locking the latter against lengthwise movement, means for flowing a liquid into the first-mentioned cylinder, means for withdrawing the liquid from the cylinder under pressure, a control valve, an air pressure supply pipe connected to said valve, pressure pipe lines extending from said valve to the outer ends of the cylinders, respectively, said valve including a valve piston movable into positions to connect said pressure pipe lines alternatively to said air pressure supply pipe and thereby alternatively apply air under pressure to the piston motor for discharging the liquid and to the plungers for returning said plungers.
